UNITED STATES PATENT OFFICE.

THOMAS W. BANTA, OF NEW RICHMOND, INDIANA.

DRAFT-EQUALIZER.

SPECIFICATION forming part of Letters Patent No. 707,539, dated August 26, 1902.

Application filed December 28, 1901. Serial No. 87,557. (No model.)

To all whom it may concern:

Be it known that I, THOMAS WESLEY BANTA, a citizen of the United States, residing at New Richmond, in the county of Montgomery and State of Indiana, have invented a new and useful Draft-Equalizer, of which the following is a specification.

This invention relates generally to draft-equalizers, and more particularly to one intended for use in connection with gang-plows; and the object of the invention is to provide an exceedingly cheap and simple appliance which can be attached to any gang-plow now in use and which will enable the draft to be applied to one side, taking off all side draft, thereby enabling the horses to travel with a direct draft and affording them all the room they need in which to travel. It also eliminates all friction on the landside, thereby making the draft much lighter.

Another object is to provide a device which will yield when any unusual tension is placed thereon—such as may be caused by the plow-points coming in contact with a stump, rock, or other obstruction—thereby avoiding the breakage of any other parts of the plow.

With these objects in view the invention consists in the novel features of construction and combination hereinafter fully described, and pointed out in the claims.

In the drawings forming part of this specification, Figure 1 is a perspective view showing the practical application of my invention. Fig. 2 is a top plan view of the same. Fig. 3 is a detail sectional view on the line 3 3 of Fig. 2, and Fig. 4 is a detail perspective view of the slotted link and folded strap to which the said link is connected.

Referring to the drawings, A indicates the plow-beams, connected at their forward ends by means of a cross-clevis B, said plow-beams A and cross-clevis B being braced by means of the angular straps C, secured to the inner faces of the said beams, and the laterally-projecting end of the cross-clevis B is further braced by means of the brace strap or band D, which extends from the end of the said projecting portion to the side of the adjacent beam A.

A clip E is rigidly secured to the end of the cross-clevis B, said clip E having a bolt passing through its center for the purpose of hold-

ing the clip to the cross-clevis, said clip E having a draft-clevis connected thereto by a long bolt standing up and down, and the draft-clevis which stands up and down is connected with the main doubletree-clevis F. A hook H is connected with the same bolt that connects doubletree-clevis with up-and-down clevis, said hook or eye having a link I connected thereto, the opposite end of said link being loosely connected to a slotted bar or plate K, said slotted bar or plate being arranged between the ends of the folded metallic strap L, a bolt L' passing through the ends of the strap and through the slot K', produced in the bar or plate, said bolt having a nut L² upon its lower end and by means of which the slotted bar or plate, which virtually constitutes a link, can be secured between the ends of the folded strap or band, thereby producing a rigid connection between the link I and the folded band or strap L.

A twisted link M connects the folded band or strap L to a spring-bar N, the said link M engaging an eye or loop N', produced upon the end of the said spring-bar, the opposite end of said spring-bar being attached to the side beam A and passing around the end of the cross-clevis B, as most clearly shown at N².

By means of draft appliance constructed and arranged as herein shown and described I am enabled to place the draft entirely at the side, and more room is thereby provided for the horses, which enables the plows to take the proper amount of land, thereby enabling the horses, plows, and gangs to travel in an easy unstrained condition. In case the plow should strike a stump, rock, or other obstruction the excessive strain placed upon the doubletree will cause the slotted bar or plate to slip between the ends of the folded strap L and all damage to the other parts of the plow will be avoided. The slotted plate can then be readjusted and the plowing operation resumed.

Having thus fully described my invention, what I claim as new, and desire to secure by Letters Patent, is—

1. The combination with the plow-beams and cross-clevis, a draft-clevis attached to the end of said cross-clevis, a spring-bar connected to the end of said plow-beam around the end of cross-clevis and the yielding connec-

tion between the side draft-clevis and the end of spring-bar, substantially as set forth.

2. The combination with the plow-beams and cross-clevis, one end of said cross-clevis 5 projecting laterally beyond the plow-beam, of a draft-clevis attached to the projecting end of the cross-clevis, a spring-bar connected to the opposite end of said plow-beam A', a yielding connection between the said spring-bar 10 and draft-clevis, said yielding connection comprising a twisted link, a folded strap or bar, a longitudinally-slotted plate, and an angular plate having a hook at one end, substantially as described.

3. In a device of the kind described, the 15 combination with the angular plate having a hook at one end, the longitudinally-slotted bar or plate connected to said link, the folded strap having a bolt passing through its ends and also through the slotted plate or bar, the 20 twisted link and the spring-bar having an eye or loop at one end adapted for engagement with the twisted link, substantially as set forth.

THOMAS W. BANTA.
